UNITED STATES PATENT OFFICE.

JAMES WATERS, OF MINNEAPOLIS, MINNESOTA.

DOUBLE-ACTING FORCE-PUMP.

SPECIFICATION forming part of Letters Patent No. 340,020, dated April 13, 1886.

Application filed April 12, 1884. Serial No. 127,674. (No model.)

To all whom it may concern:

Be it known that I, JAMES WATERS, a citizen of the United States, and a resident of Minneapolis, in the county of Hennepin, in 5 the State of Minnesota, have invented certain new and useful Improvements in Double-Acting Force-Pumps, of which the following specification is a full, clear, and exact description, reference being also had to the accompanying drawings, in which—

Figure 1 is a horizontal sectional view on the line $x x$ of Fig. 2. Fig. 2 is a vertical section on the line $y y$ of Fig. 1. Fig. 3 is a vertical section on the line $z z$ of Fig. 2. Fig. 4 15 is a horizontal section of the vacuum-chamber on the line $w w$ of Fig. 3.

This invention relates to double-acting force-pumps; and it consists in the construction and arrangement of parts hereinafter shown, and 20 specifically defined by the claim.

The pump-casing consists of a vacuum-chamber, a central chamber, and an air-chamber, the said central chamber being placed between the vacuum-chamber and air-chamber, and 25 divided into compartments, and each compartment provided with an independent plunger and set of valves.

A' represents a base-plate, upon which is secured a cylindrical chamber, A^2 , having a 30 closed top, A^3 , the whole forming the vacuum-chamber above mentioned. a is a suction or inlet pipe leading into this vacuum-chamber, and $b' b^2$ are two tubes projecting downward into the chamber from the under side of the 35 top A^3 , as shown. The sides of these tubes are connected to each other and to the sides A^2 of the chamber by webs b^3 , so that the tubes and webs form a division-wall across the chamber, extending down a little more than half-way to the base A' , thereby partially dividing the vacuum-chamber into two compartments, 40

$A^4 A^5$, into one of which the inlet-pipe a leads. Valve-ports c' are formed through the top A^3 into the tubes $b' b^2$, and each set of ports is 45 provided with a spring-valve, d' and d^2 , opening upward, as shown. Upon top of this vacuum-chamber is secured the central chamber above mentioned, consisting of a tubular section, B' , of the same diameter, but longer than 50 the cylindrical section A^2 of the vacuum-chamber, and provided with a closed top, B^2 , as

shown. Upon the top of this central chamber is secured the air-chamber C , above mentioned, the top B^2 of the central chamber forming a division between the central and air chambers, 55 and the top A^3 of the vacuum-chamber forming a division between the central and vacuum chambers.

The top B^2 of the central chamber is provided with ports c^2 and spring-valves d^3 , directly above and similar to the ports c' and valves $d' d^2$ of the vacuum-chamber. Thus the only communication between the central chamber and the vacuum-chamber and between the central chamber and the air-chamber is through the ports $c' c^2$ and valves $d' d^2 d^3$. 60

D is the discharge or outlet formed in the top B^2 , and leading down through the upper part of the central chamber and out through its side. By this manner of arranging the discharge-pipe the air-chamber can be removed 65 without the necessity of disconnecting the discharge-pipe or disturbing other parts of the pump-casing. 70

The central chamber is divided through the center by a division-wall, B^3 , at right angles to the division-wall formed by the tubes $b' b^2$ and webs b^3 in the vacuum-chamber, thereby forming the central chamber into two separate compartments, with a pair of the valves $d' d^2$ 80 d^3 leading into and discharging from each compartment. 75

Formed in the sides of the central chamber, near its top, are two plunger-cylinders, $E' E^2$, one opening into each of the separate compartments formed by the wall B^3 , and each cylinder provided with a hollow plunger, $F' F^2$, suitably packed by stuffing-boxes $e' e^2$. The inner ends of these plungers are formed cone-shaped, as shown at $g' g^2$, and with their opposite ends opening outward through the stuffing-boxes. 85

$h' h^2$ are two "blocks" or "heads" fitting into the inner ends of the plungers $F' F^2$, and secured therein by bolts $i' i^2$, tapped into them 95 through the points of the conical ends $g' g^2$. These heads are formed with slots $K' K^2$ across them in one direction, and with large pins $m' m^2$ fitting through them at right angles to the slots. 90

$G' G^2$ are two arms or brackets attached to or formed in one piece with the central cham- 100

ber, and provided with bearings n' n^2 on their outer ends, in which a crank-shaft, H' , is journaled, as shown. This crank-shaft is provided with two oppositely branching cranks, H^2 H^3 , attached by connecting rods I' I^2 and straps I^3 I^4 to the pins m' m^2 in the heads h' h^2 . By this means the revolution of the crank-shaft will move the plungers F' F^2 outward and inward alternately, and cause the water to be drawn up through the inlet a and valves d' d^2 and discharged through the valves d^3 into the air-chamber C , and thence out through the discharge-pipe D' .

By dividing the central chamber into two compartments and providing each compartment with its own independent plunger and set of valves, I form a double-acting pump with one inlet and one outlet chamber common to both. By this form of the casing and plungers a very high speed may be given to the plungers without danger of breaking the pump or bursting the pipes from the pressure of the water, as the latter merely follows the plungers when they recede, and by the conical form of the inner ends of the plungers when they are forced inward again they very easily and smoothly displace a quantity of the water equal to their bulk, and force it up through the valves d^3 without any sudden pressure or "pounding," as generally results from the action of the ordinary form of pump. There is also an advantage in arranging the plungers to operate in opposite directions, as the plungers thereby balance each other, so that no straining of the casing occurs when running at a high rate of speed. This arrangement avoids the necessity of mounting the pump upon heavy and expensive foundations, as all the strains are exerted between the crank-shaft and the pump-casing, and even this strain is greatly reduced by the oppositely moving plungers balancing each other, as above described.

The dividing of the vacuum-chamber into two compartments by the webs b^3 and tubes b' b^2 is also a very important feature of my invention, as that part of the chamber on the opposite side of the tubes and webs from the inlet a forms a reservoir or space, into which the air already in the chamber and what is carried in by the inflowing water escapes, so that it will not be carried up into the central chamber.

An additional air-chamber, A^6 , as shown in dotted lines in Fig. 2, may be attached to the vacuum-chamber A^4 , if desired.

The valves d' d^2 d^3 are of rubber or other flexible material; hence less noise occurs at their rising and falling than if they were formed of metal, and by the peculiar form of the plungers and driving mechanism their operation is almost noiseless; hence pounding and other noises are greatly reduced.

The shaft will be coupled to or will form the main shaft of the engine which drives the pumps; hence no gearing or belting is neces-

sary to connect the pump with the motive power, thereby dispensing with a large amount of extra machinery and apparatus. This direct connection could not be used with the ordinary form of pump, as the motion would be too great. By my arrangement, however, the pumps can be run up to a speed of one hundred or more revolutions per minute, so that the pumps can be connected directly to the main shaft of any high-speed engine, and without interfering with the ordinary use of the engine for other purposes besides operating the pumps.

This pump will be found particularly adapted for use in forcing water up to the tanks used to operate freight and passenger elevators in buildings, and also to force water to the upper floors of buildings for ordinary use. The pump will also be found to operate very advantageously in connection with gas or caloric engines and other small high-speed motors.

Great annoyance has heretofore occurred from the pounding or jarring noise produced in the water-pipes running through buildings where the water has been forced into said pipes by pumps located on or near the premises, as the noise of the pumps and of the pressure of the water is carried throughout the building by the vibrations and sound-conducting qualities of the metal pipes. I partially prevent this jarring by the smooth, concussionless manner in which my form of pump acts upon the water; but to entirely prevent this jarring and vibration of the pipe, I arrange in the discharge-pipe D' a section of tubing formed of a material which is a non-conductor of sound. This non-conductor material may be formed of rubber or leather hose Z , (see Figs. 1 and 2,) or any other similar material which is strong enough to withstand the pressure of the water; or a section of wooden or soft-metal tubing may be used under some circumstances. The pipe D' may be wrapped in felt or other soft flexible substance; or the tube may be buried in the earth for a short distance, or any other means used to partially or entirely nullify the sound-conveying qualities of the piping. By this means what little noise is made by the action of the pumps, engine, &c., will not ascend to the rooms above.

The very rapid movement of the plungers has a tendency to carry air in with them and force it in past the packing in the stuffing-boxes into the central chamber, and if a sufficient quantity thus finds its way in, it will greatly interfere with the action of the pumps. To prevent any such results, I connect the air-chamber C to each of the cylinders by a tube or "duct," whereby a pressure of water or a water-packing may be provided between the outside of the plunger and the inside of the cylinders, this water-pressure being greater than the air-pressure, so that no air can pass into the cylinder-chamber between the plun-

gers and cylinders. Any suitable means may be used for making this water connection between the air-chamber and the cylinders, either by boring a hole, n^3 , down into the partition B^3 , and connecting this hole with the cylinders by a cross-hole, n^4 , or by connecting the air-chamber and cylinders by tubes t^1 t^2 , as shown by dotted lines in Fig. 3, or in any other suitable manner. The former means is preferable, however. Small grooves n^5 will be turned out of the inside of the cylinders opposite the point where the water from the air-chamber enters, so that the water will be free to flow entirely around the plungers and pack them equally on all sides.

The two compartments of the central chamber will be connected by a tube, L' , having a valve, L^2 , so that the pressure in the two compartments may be equalized, if required. In first starting the pumps it is sometimes necessary to thus equalize the pressure, and by this simple arrangement it may be easily accomplished by merely opening the valve L^2 , and the communication will be closed when the pumps are running regularly by closing the same valve.

M' is another pipe arranged to connect the air-chamber with one of the compartments of the central chamber, and provided with a valve, M^2 , whereby a supply of water may be

admitted to the central chamber to "prime" the latter when first starting the pump.

N' is a "petcock" to allow the air to escape from the compartments of the central chamber, and N^2 is a similar cock to admit air to the vacuum-chamber.

P' P^2 are "hand-holes" leading into the central chamber, through which the valves and interior of the compartments may be inspected and repaired without removing the central chamber.

Having described my invention and set forth its merits, what I claim is—

The combination of the plunger F' F^2 , open to the outer air, the water-chambers in which the plungers work, the air-chamber C , communicating with the water-chambers, and the plunger-cylinders E' E^2 , having water-ducts h^3 h^4 , leading from the air-chamber to the inner surfaces of the said plunger-cylinders, whereby the pressure on the water in the ducts from the outer air, water in the water-chambers and in the air-chamber is equalized, for the purpose herein set forth.

In testimony whereof I have hereunto set my hand in presence of two subscribing witnesses.

JAMES WATERS.
